(57) CLAIM

The ornamental design for a food grater, as shown and described.

DESCRIPTION

FIG. 1 is a front view of the support block of a food grater showing my design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a left side view of the grater plate of a food grater;

FIG. 8 is a right side view thereof;

FIG. 9 is a top view thereof;

FIG. 10 is a bottom view thereof;

FIG. 11 is a front view thereof;

FIG. 12 is a rear view thereof;

FIG. 13 is a front perspective of the food grater with the grater plate assembled with the support block; and,

FIG. 14 is a front perspective view thereof with a piece of salt positioned on the support block.

The broken lines in FIG. 14 are for illustrative purposes only and do not form part of claimed design.

The support block and grater are shown separately for clarity of illustration.
